UNITED STATES PATENT OFFICE.

JAMES FRASER, OF DUNDEE, AND JAMES GAVIN FRASER AND HUGH WALKER, OF ABERDEEN, SCOTLAND.

ROVE-STOP MECHANISM.

SPECIFICATION forming part of Letters Patent No. 655,860, dated August 14, 1900.

Application filed March 29, 1900. Serial No. 10,647. (No model.)

To all whom it may concern:

Be it known that we, JAMES FRASER, late mill-manager, residing at Dundee, in the county of Forfar, and JAMES GAVIN FRASER, engineer, and HUGH WALKER, carpenter, residing at Aberdeen, in the county of Aberdeen, Scotland, subjects of the Queen of Great Britain and Ireland, have invented certain new and useful Improvements in Rove-Stop Mechanism, (for which applications for patent have been applied for in Great Britain, No. 5,154, dated March 9, 1899, and No. 3,234, dated February 19, 1900,) of which the following is a specification.

The objects of the invention are improvements in rove-stop mechanism for spinning-machines; and it consists, essentially, in the use, in combination with a hackle-gill, of a tumbling or throwing-out weighted or spring-actuated lever and fittings for throwing the rove or yarn to one side to clear it from the grip of the retaining-rollers, and so stop delivery of the rove without stopping the rollers when the roving breaks on its way to the flier or other twisting mechanism.

Referring to the drawings, which form part of this specification, Figures 1 and 2 are respectively side sectional and front elevations of parts of a spinning-machine, showing the tumbling-lever fitted in front of the retaining-rollers. Figs. 3 and 4 are respectively side sectional and front elevations of parts of a spinning-machine, showing the tumbling-lever fitted behind the retaining-rollers, while Figs. 5 and 6 are similar views illustrating another method of fitting the tumbling-lever behind the retaining-rollers. Figs. 7 and 8 are similar views showing the tumbling-lever fitted between the retaining-rollers.

As shown in Figs. 1 and 2, the tumbling or throwing-out lever *a* is pivoted on the pin *b* on a bar *b*, secured in front of the retaining-rollers *c d*, and is formed with a bent-over top part formed with an eye or loop *a'* at its end and has a weight *a''* secured on it. The tumbling-lever *a* rests against the stop *e* and is held up in a position slightly off the perpendicular by the trigger or releasing rod *f* working through the guide *g* and secured by its lower end to the oscillating arm or lever *h*,

pivoted on the rail *i* of spinning-machine at *j*. This long oscillating arm *h* also carries the curved arm *k*, on which is secured the hackle-gill *l*. The rove *R* passes through the eye *a'* on its way to the retaining-rollers *c d*, whence it passes over the rove-plate *m* to the drawing-rollers *n o*, from which it passes to the flier or other twisting mechanism. While the yarn remains unbroken it holds up the trigger-rod *f* in its stopping position against the tumbling-lever *a* by pressing on the bent end *h'* of the arm *h*, connected to the trigger-rod *f*; but if the yarn breaks the trigger-rod *f* by the fall of the arm *h* is released and allowed to fall to release the tumbling-lever *a*, which as it falls to one side draws the rove *R* from between the retaining-rollers and so stops delivery. At the same time the hackle-gill *l* is moved forward to catch or intercept the rove. When the spinner pulls the end *h'* of the arm *h* forward and replaces the tumbling-lever *a* in its normal working position, the free end of the spring *f'*, secured to the trigger-rod *f*, rises over the stop-pin *e* and automatically upholds the rod *f* and lever *a* until the rove is again in running working order, when the arm *h* is restored to its normal working position, with its end *h'* supported by the rove, the trigger-rod by the same action being lowered till the end of the spring *f'* falls below the stop-pin *e*. The spring *f'* is secured to the rod *f* in any suitable manner—for instance, by one of its ends passing through an opening in the rod—and its free end is shown at *f''* in Figs. 1 and 3. This end while flexible is sufficiently stiff to hold the rod *f* up by engaging the upper side of the stop-pin *e* when the spinner raises the rod.

As shown in Figs. 3 and 4, the tumbling or weighted throwing-out lever *a*, fitted behind the retaining-rollers *c d*, is bent to avoid contact with the back roller and is pivoted on the stud-pin *b'*, secured on the bracket *i'* on the rail *i* of spinning-machine. The trigger rod or lever *f* is also bent and is pivoted on the stud-pin *f'* and has its upper end *f''* bent over hook shape to engage with and hold up the tumbling-lever *a* so long as the yarn remains unbroken. The lower end *f'''* of the trigger-lever *f* is bent to one side and passed through an eye on the end of the short arm of the

lever h^2 . The pressure of the rove on the bent end h' of the arm h holds it back against the bent arm a^3 , which acts as a stop and prevents the eye h^2 from acting on the angled arm f^3 to shift the trigger-arm and release the tumbling-lever a . When the yarn breaks, the lever h^2 is allowed to fall sidewise, and by its eye h^2 it acts on the angled arm f^3 of the trigger-lever ff^3 and by disengaging the hook part f^2 allows the lever a to fall to one side and by so falling draw the rove by its eye or loop a' (or it may be simply a fork) from between the retaining-rolls $c d$. The hackle-gill l at the same time moves sidewise with the lever h^2 to intercept and catch the rove by its teeth. The hook f^2 also temporarily sustains the tumbling-lever a while the spinner replaces the rove in running order.

As shown in Figs. 5 and 6, the tumbling-lever a is fitted behind the retaining-rolls, but is released in a different manner. In this case the tumbling-lever a is upheld while the yarn remains unbroken by the point of the trigger-rod f , which slides in a tube f^6 , secured to the bracket i' , and has its lower end angled upward at f^8 . When the yarn breaks, the lever h^2 acts by means of its eye h^2 on the angled end f^3 of the trigger-rod f , and drawing it down releases the tumbling-lever a , which stops the delivery of the rove by drawing it from between the retaining-rolls $c d$. While the spinner is replacing the rove the tumbling-lever a is temporarily upheld by the spring f^4 , (shown in Fig. 5,) the end of which rises over the lever a when the arm h is pulled to one side in an equivalent manner to the spring shown in Figs. 1 and 2 and falls below when the arm h is in normal working position.

By another arrangement, as shown in Figs. 7 and 8, the tumbling-lever a is fitted between the retaining-rolls in the space between the shafts carrying the same and is fulcrumed on the carrier-bar b , bolted to the bearing-bar b^2 of spinning-machine, while the yarn remains unbroken, the weighted lever a , upheld by the trigger or slip rod f , passing through the guide g and secured at its lower end to the arm h , pivoted at j , which carries the hackle-gill l and its supporting-arm k . When the yarn breaks, the arm h falls back and the slip-rod f , secured to same, moves downward and releases the tumbling-lever a , which is caused by the weight a^2 to fall to one side and draw, by means of its hook a' , or it may be a fork, the rove from between the retaining-

rollers $c d$. The hackle-gill l at the same time moves forward to intercept the rove. While the spinner is replacing the rove the tumbling-lever a is temporarily upheld by the projection f^5 on the trigger f , which by the forward pull of the arm h is caused to rise above the bent upper part of the lever a and rest on it until the arm h is placed in normal working position supported by the rove. 65

We have shown weights applied directly to the throw-out levers a ; but it will be understood that the equivalent device—a spring—may also be applied to give the same action as the weight. 70

Having now described our invention, what we claim as new, and desire to secure by Letters Patent, is—

1. In combination, a weighted tumbling throw-out lever, a sustaining or releasing trigger-rod engaging the throw-out lever, a hackle-gill, a lever carrying the same, said lever having an end h' to engage the rove and hold the hackle-gill out of contact with the rove and a connection between said hackle-gill lever and the trigger whereby when the rove breaks the hackle-gill lever will operate to withdraw the trigger and move the hackle-gill into the path of the rove, substantially as described. 85

2. In combination, a weighted tumbling throw-out lever, a sustaining or releasing trigger-rod engaging the throw-out lever, a hackle-gill, a lever carrying the same, said lever having an end h' to engage the rove and hold the hackle-gill out of contact with the rove and a connection between said hackle-gill lever and the trigger whereby when the rove breaks the hackle-gill lever will operate to withdraw the trigger and move the hackle-gill into the path of the rove, and a spring f^4 carried by the trigger to hold the tumbling-lever in position while the parts are being reset, substantially as described. 95

In testimony whereof we have signed our names to this specification in the presence of the subscribing witnesses.
